UNITED STATES PATENT OFFICE.

JOB HUTCHINSON, OF NEW YORK, N. Y., ASSIGNOR TO NATIONAL INDICATOR COMPANY,
A CORPORATION OF NEW YORK.

FLUID-PRESSURE CONTROL OF TRANSOMS AND WINDOWS.

1,054,417.

Specification of Letters Patent.

Patented Feb. 25, 1913.

Application filed July 17, 1907, Serial No. 384,232. Renewed November 21, 1912. Serial No. 732,798.

To all whom it may concern:

Be it known that I, JOB HUTCHINSON, a citizen of the United States, residing at New York, in the county of New York and State of New York, have invented certain new and useful Improvements in Fluid-Pressure Control of Transoms and Windows, of which the following is a specification.

10 My invention relates to the fluid pressure control of transoms and windows, and especially to the control of the heavy transoms of large windows, and the large heavy windows themselves, of hotels and office buildings.

One of the objects of the invention is to provide a system in which the transom or window is operated by compressed air acting upon a piston and controlled by a valve 20 in such a manner that the rapidity of opening may be regulated with certainty and slamming in closing will be absolutely prevented.

Another object is to provide an improved 25 piston construction by which the transom or window is securely held in any desired position when pressure is admitted to both sides thereof simultaneously.

Another object is to provide an improved 30 connection between the operating piston and a transom.

Another object is to provide an improved 35 controlling valve by which pressure may be admitted to either side of the operating piston and exhausted from the other, and by which pressure may be admitted to both sides of the piston simultaneously.

Another object is to provide an adjustment 40 for the exhaust from the operating cylinder to prevent slamming of the transom or window.

Another object is to provide a system in which a number of transoms or windows, such as all upon a floor of the building, 45 may be controlled by means of a master valve conveniently situated, as in the corridor, so that they may be closed or opened in case of storm without entering the rooms.

With these and other objects in view, the 50 invention consists in the novel arrangement of parts and improved details of construction hereinafter described, and illustrated in the accompanying drawings; in which drawings—

55 Figure 1 is a view in front elevation

showing the double transom of a large window equipped in accordance with my invention; Fig. 2 is a side elevation on a larger scale showing the operating cylinder and the connection between its piston rod 60 and the transom; Fig. 3 is a vertical section through the operating cylinder showing the construction of the piston; Fig. 3^a is a detail showing the piston when pressure is exerted simultaneously on both sides thereof; Fig. 3^b is a similar view of a slight modification; Fig. 4 is a top plan view of the controlling valve, the movable element being shown in an extreme position and the ports being shown in dotted lines; Fig. 5 is 65 70 a central section of the same valve, the movable element being shown in its intermediate position; Fig. 6 is a view similar to Fig. 2 showing a modified form of connection between the operating piston rod and 75 the transom; Fig. 7 is a view in elevation showing some features of my improvements applied to raise and lower a counter-weighted window-sash; and Fig. 8 is a similar view of the same applied to an uncounter-weighted window.

Referring to the drawings, A represents a window frame, and B a transom of which two constituting a pair are shown in Fig. 1. Transoms B are pivoted at b, and 85 mounted on the fixed frame between them is the operating cylinder C containing piston D. Piston D is preferably of special construction, and consists of two plates d, d' mounted upon the reduced end of piston rod d² with a compressible pad d³ preferably of soft rubber between them. As shown in Figs. 3 and 3^a, plate d is fixed upon the end d⁴ of the piston rod in any suitable manner, as by being threaded 90 thereto, and plate d' is movable, being pressed against a shoulder on the piston-rod by coiled spring d⁵. The periphery of compressible pad d³ normally just clears the cylinder walls, but when pressure is admitted to both sides of the piston the pad d³ is compressed to grip the cylinder walls and also act as a packing. If desired, plate d' may be secured to piston rod d², 95 and plate d movable, as shown in Fig. 3^b. 100 105

The form of connection between piston rod d² and the transoms shown in Figs. 1, 2 and 3 comprises a member E oppositely mounted upon the frame of each transom in proximity to the hinge or pivot b, and 110

formed with a longitudinal slot e . Pivot-
ed at e' upon the fixed frame adjacent
each transom is an arm e^2 , these arms being
connected by bar e^3 extending between offset
portions thereof. Each arm e^2 carries at its
outer end a pin e^8 engaging slot e of member
E. Bar e^3 works in slot e^5 of end block e^6
mounted upon piston rod d^2 , this end block
sliding in a groove e^7 upon the fixed frame.
10 Besides being connected by bar e^3 of arms
 e^2 , the transoms are connected at their upper
ends by a strip b^2 which causes them to move
together.

In some instances I may omit slotted mem-
bers E, and form arms e^2 as shown in Fig. 6.

Operating cylinder C is connected with a
source of pneumatic pressure by pipes 1 and
2, pipe 1 communicating with the upper end
of the cylinder above the piston D, and pipe
2 communicating with the lower end of the
cylinder by port c below the piston. These
pipes 1 and 2 are connected with a general
supply pipe 3 which may extend throughout
the building or one of the floors thereof and
supply pressure to any desired number of
transoms or window operating devices. The
connection with this supply pipe 3 is made
from an inlet pipe 4 through a controlling
valve F, shown in detail in Figs. 4 and 5.
30 This controlling valve has supply ports 5
and 6, also exhaust port 7, located in the
casing or fixed portion thereof. The mov-
able member f of the valve, operated by
handle f', is provided with a central supply
port 8 and exhaust ports 9 and 10, one lo-
cated on each side of the supply port. These
ports in the movable member f of the valve
are so arranged that when said movable
member is in either of its extreme positions
one of the exhaust ports 9 or 10 will con-
nect the inlet pipe 4 with one of the supply
ports 5 or 6, and the other will connect the
remaining supply port, say 6, with exhaust
port 7, thereby supplying pressure to one
45 side of the piston D and exhausting it from
the other side. When the movable member
f is in a central position, the central supply
port 8 will be in communication with both
of supply ports 5 and 6 through auxiliary
ducts 11 and 12.

One of the important features of my in-
vention consists in the regulation or adjust-
ment of the exhaust port 7 which is effected
by means of a small screw f² having a duct
f³, the communication of which with exhaust
port 7 is either increased or diminished by
the turning in or out of the screw. An ad-
justment is also provided in the fixed supply
ports 5 and 6 by means of screws f⁴, f⁵, these
60 screws being usually adjusted to admit a
larger amount of fluid to the cylinder than
is permitted to exhaust therefrom by screw
f², so that there will be no conflict between
the two adjustments.

65 In Fig. 7, I have shown a modification of

my invention in which a counter-weighted
window W is operated by means of a piston
working within cylinder C and controlled
by a two-way valve F' provided with ex-
haust adjustment f² similar to that shown in
70 Figs. 4 and 5. The window shown in this
Fig. 7 is operated positively in both raising
and closing, while that shown in Fig. 8 is
without a counter-weight and is raised only
by a single-acting piston within cylinder C
75 controlled by valve F², as shown.

The operation of the various parts of my
invention will be apparent from the fore-
going description, and is as follows: When the
operating handle f' of valve F occupies the
position shown in Fig. 4, pressure is ad-
mitted through supply pipe 1 above the pis-
ton D in cylinder C, thereby pressing said
piston downward and exerting pressure
upon rod e³ which thereupon slides out-
wardly in slot e⁵ of end block e⁶. This
throws arm e² outward and exerts pressure
upon members E by pins e⁸, thereby opening
both transoms. In order to close the trans-
oms the operating handle is placed in the
other extreme position, when the above ac-
tion is reversed, pressure being admitted to
supply pipe 2 and exhausted from supply
pipe 1. In the movements in both directions
the exhaust adjustment f² operates to pre-
95 vent too sudden opening or closing, or slam-
ming, of the transoms thereby preventing
breakage. In order to hold the transom in
any desired position the operating handle
of valve F is placed in its intermediate
position, shown in Fig. 5, in which the side
ports 9 and 10 of the movable member are
100 disconnected from the ports of the fixed por-
tion of the valve and the central supply port
8 is connected to both of the fixed ports 5
and 6 through ducts 11 and 12, thereby ad-
mitting pressure to both sides of the pis-
ton D, compressing the compressible pad d³
which expands and grips the piston walls
firmly, thereby holding the piston in that
110 position and preventing the leakage of air
from one side to the other thereof. It is to
be noted that transoms are usually so pivoted
that they have a tendency to close, and there-
fore the greater operating force must be ex-
erted downward upon the pistons to open
the transoms. The spring d⁵ is made suffi-
ciently strong to resist the relative movement
of plates d, d' under pressure admitted to
the piston to operate it in either direction,
120 but yieldable to permit the compression of
pad d³ when pressure is admitted to both
sides of the piston.

As above indicated, any number of trans-
oms or windows may be operated from sup-
ply pipe 3 either by individual valves or by
a master valve located at some convenient
point such as the corridor through which ac-
cess is had to the rooms. In this way all of
the windows on a single floor of a hotel may
130

be closed in case of storm without entering the rooms, and may be again opened after the storm is passed.

It is obvious that instead of operating a double transom by a single valve, a separate valve may be provided for each transom, and many other changes and modifications may be made in the apparatus hereinbefore described without departing from the invention.

Having described my invention, what I claim as new and desire to secure by Letters Patent of the United States, is—

1. In a closure controller, the combination with a closure and a piston operatively connected therewith, of a cylinder for said piston, a valve, pressure supply and exhaust lines for admitting pressure to and exhausting it from said cylinder, an adjustable device for controlling the rate of flow through the admission line, and an adjustable device to limit flow rate through the exhaust line to an amount less than that through the admission line, substantially as described.

2. In a closure controller, the combination with a closure, a cylinder, a piston for said cylinder operatively connected with said closure and provided with a compressible element arranged to grip said cylinder walls when compressed, a valve, pressure supply and exhaust lines to admit pressure to and exhaust it from said cylinder at either side of said piston to operate the same, and to connect both sides of said piston to a source of pressure simultaneously to compress said compressible element and hold the piston stationary, an adjustable device for controlling the rate of flow through the admission line, and an adjustable device to limit flow through the exhaust line to an amount less than that through the admission line, substantially as described.

3. In a closure controller, the combination with a closure and a piston operatively connected therewith, of a cylinder for said piston, a valve provided with fixed ports for admitting pressure to and exhausting it from said cylinder at either side of said piston, an adjustable device to regulate the rate of flow through the exhaust port of said valve, and a movable element in said valve having ports arranged to connect one side of said piston to the admission port and the other side of said piston to the exhaust port when in its extreme position, and to connect both sides of said piston to the source of pressure when in an intermediate position, substantially as described.

4. In a closure controller, the combination with a closure, of a piston operatively connected therewith and constructed with plates, one of which is movable, and with a compressible element between said plates, a cylinder for said piston engaged by the compressible element when said element is

compressed, a valve provided with fixed ports for admitting pressure to and exhausting it from said cylinder at either side of said piston, and a movable element in said valve having ports arranged to connect either side of said piston to a source of pressure and said exhaust, or to connect both sides of said piston to a source of pressure to compress said compressible device and hold the piston stationary, substantially as described.

5. In a closure controller, the combination with a closure, a cylinder, a piston for said cylinder operatively connected with said closure and provided with a compressible element arranged to grip said cylinder walls when compressed, and a controlling valve constructed to admit pressure to and exhaust it from said cylinder at either side of said piston to operate the same, and to connect both sides of said piston to a source of pressure simultaneously to compress said compressible element and hold the piston stationary, substantially as described.

6. In a closure controller, the combination with a closure, a cylinder, a piston for said cylinder operatively connected with said closure and constructed with plates one of which is movable with respect to the other, an annular resilient compressible element between said plates arranged to grip said cylinder walls and form a packing when compressed, and a controlling valve constructed to admit pressure to and exhaust it from said cylinder at either side of said piston to operate the same, and to connect both sides of said piston to a source of pressure simultaneously to compress said compressible element and hold the piston stationary, substantially as described.

7. In a closure controller, the combination with a closure, a cylinder, a piston for said cylinder operatively connected with said closure and constructed with plates one of which is movable with respect to the other, an annular resilient compressible element between said plates arranged to grip said cylinder walls and form a packing when compressed, a controlling valve constructed to admit operative pressure to said cylinder at either side of said piston, and to connect both sides of said piston to a source of pressure simultaneously to compress said compressible element for holding the piston stationary, and means for preventing said compression except when pressure is admitted to both sides of said piston, substantially as described.

8. In a closure controller, a cylinder, a piston rod, and a piston therefor within said cylinder provided with a compressible element arranged to grip said cylinder walls and hold said piston stationary when compressed, substantially as described.

9. In a closure controller, a cylinder, a

piston rod, a piston therefor within said cylinder constructed with plates one of which is movable with respect to the other, and a compressible element between said plates arranged to grip said cylinder walls and hold said piston stationary when compressed, substantially as described.

10. In a closure controller, a cylinder, a piston rod, a piston therefor within said cylinder constructed with plates one of which is movable with respect to the other, and an annular rubber compressible element between said plates arranged to grip said cylinder walls and hold said piston stationary when compressed, substantially as described.

11. In a closure controller, the combination with a closure and a piston operatively connected thereto, of a cylinder for said piston, a valve for admitting pressure to said piston and for exhausting pressure therefrom to move the closure in opposite directions, an exhaust flow-rate controlling device, and regulating means for varying the flow-rate of the supply pressure without affecting the exhaust flow-rate.

12. In a closure controller, the combination with a closure and a piston operatively connected thereto, of a cylinder for said piston, a valve for admitting pressure to said piston through either of two lines of supply and for exhausting pressure therefrom to a single exhaust line to move the closure in opposite directions, and independent regulating means for each line of supply for varying the flow-rate of supply pressure without affecting the exhaust flow-rate.

13. In a closure controller, the combination with a closure and a piston operatively connected thereto, of a cylinder for said piston, a valve for admitting pressure to said piston through either of two lines of supply and for exhausting pressure therefrom to a single exhaust line to move the closure in opposite directions, an exhaust flow-rate controlling device, and independent regulating means for each line of supply for varying the flow-rate of supply pressure without affecting the exhaust flow-rate.

14. In a closure controller, the combination with a closure and a piston operatively connected thereto, of a cylinder for said piston, a valve for admitting pressure to said

piston through either or both of two lines of supply and for exhausting pressure therefrom to a single exhaust line to move the closure in opposite directions or retain it balanced, an exhaust flow-rate controlling device, and independent regulating means for each line of supply for varying the flow-rate of supply pressure without affecting the exhaust flow-rate.

15. In a closure controller, the combination with a closure and a piston operatively connected thereto, of a cylinder for said piston, a valve, two lines of pressure supply leading to said piston from said valve, a single exhaust pressure line leading from said valve, said supply and exhaust pressures being adapted to move the closure to and from a closed position, and an independent flow-rate regulating device positioned in each of said lines, whereby variations in the flow-rate of the supply lines may be had without affecting the flow-rate of the exhaust line.

16. In a closure controller, the combination with a closure and a piston operatively connected thereto, of a cylinder for said piston, a valve for admitting pressure to said piston and for exhausting pressure therefrom to move the closure in opposite directions, said valve being movable to provide a balancing pressure to opposite sides of the piston to retain the latter in relative fixed position for holding the closure stationary.

17. In a closure controller, the combination with a closure and a piston operatively connected thereto, of a cylinder for said piston, a valve for admitting pressure to said piston and for exhausting pressure therefrom to move the closure in opposite directions, said valve being movable to provide a balancing pressure to opposite sides of the piston to retain the latter in relative fixed position for holding the closure stationary, and a regulating device for controlling the flow-rate of said exhaust.

In testimony whereof I have hereunto set my hand in the presence of two subscribing witnesses.

JOB HUTCHINSON.
